A. GIACCONE,
 THERMOSTATIC CONTROLLER FOR SIGNAL APPARATUS,
 APPLICATION FILED NOV. 28, 1916.
1,287,667. Patented Dec. 17, 1918.

UNITED STATES PATENT OFFICE.

ALEXANDER GIACCOME, OF BROOKLYN, NEW YORK.

THERMOSTATIC CONTROLLER FOR SIGNAL APPARATUS.

1,287,667.

Specification of Letters Patent. Patented Dec. 17, 1918.

Application filed November 28, 1916. Serial No. 133,968.

To all whom it may concern:

Be it known that I, ALEXANDER GIACCOME, a citizen of the United States, and residing at Brooklyn, in the county of Kings and 5 State of New York, have invented certain new and useful Improvements in Thermo- 10 static Controllers for Signal Apparatus, of which the following is a specification, such as will enable those skilled in the art to 15 which it appertains to make and use the same.

This invention relates to thermostatic controllers for signal apparatus and particularly apparatus of this class designed for 15 use in factories and other buildings where a number of people are employed for the purpose of signaling to the various parts, compartments or divisions of the building in case of fire so as to give those in the building 20 an opportunity to escape before it is too late; a further object being to provide an apparatus which, in addition to being used for the purpose specified, may also be used for other purposes, as for instance, for releasing the valve or other devices used in connection with water pipes employed in what are known as shower systems for extinguishing fire; a still further object being to provide means, in an apparatus of the 25 class specified, whereby the degree of heat necessary to operate the apparatus may be regulated; and with these and other objects in view the invention consists in an apparatus of the class specified constructed and 30 operating as hereinafter described and claimed.

The invention described and claimed herein is an improvement on that described and claimed in a prior application filed by me 40 Dec. 15, 1915, Serial No. 66,897, and said invention is fully disclosed in the following specification, of which the accompanying drawing forms a part, in which the separate parts of my improvement are designated by 45 suitable reference characters in each of the views, and in which:

Figure 1 is a plan view of one form of my improved apparatus;

Fig. 2 a bottom plan view of one part of 50 the apparatus shown in Fig. 1 and showing said part on an enlarged scale and partly in section;

Fig. 3 a transverse section on the line 3—3 of Fig. 2 and on an enlarged scale;

55 Fig. 4 a view similar to Fig. 3 but show-

ing only a detail of the construction on an enlarged scale and in section;

Fig. 5 a transverse section on the line 5—5 of Fig. 4; and,

Fig. 6 a view similar to Fig. 5 but showing a modification.

In the practice of my invention, as shown in the drawing, I provide a main hood frame *a*, comprising parallel end members *a*² of wood or any other suitable non-conducting 65 material, and a hood member *a*³ in which the end members *a*² are secured, and said hood frame is preferably rectangular in form, the bottom thereof being open.

Within the hood frame and in the opposite side portions thereof are secured two parallel, similar and conductor frames *b*, consisting of parallel outer metal strips *b*² having inwardly directed end members *b*³ to the bottom of which are secured parallel 75 metal strips *b*⁴, and the frames *b* are secured in the hood frame by screws *c* which are passed outwardly through the end portions *b*³ of the parts *b*² and through the end members *a*² of the hood frame, and which constitute binding posts for the electric wire 80 connections as hereinafter described.

The end members *b*³ of the frame members *b* are connected by longitudinal wires *b*⁵, any desired number of which may be 85 employed, and the longitudinal frame members *b*² and *b*⁴ of the frames *b* are also connected by transversely arranged wires *b*⁶.

Rigidly secured to the parallel parts *b*² and *b*⁴ of the frame members *b* are alternately arranged contact fingers *d* which range transversely of the device, and these fingers *d* are preferably secured in the frame members *b* as shown, and are preferably soldered to the frame members *b*⁴ at *e*, and 95 said fingers are bent downwardly to form parallel central portions *d*² and upwardly directed free end portions *d*³ which are designed, under the influences of changes in temperature, to make and break contact with 100 the parts or strips *b*⁴ of the frame members *b*.

The central parallel parts *d*² of the fingers *d* are weakened by reducing the transverse dimensions thereof, as shown in Figs. 105 4 to 6 inclusive, and this weakened portion extends from end to end of the central parts *d*² of said fingers, and employed in connection therewith is a longitudinal strip *d*⁴ of steel which is placed thereon and secured 110

thereto by a wire coil d^5 wrapped securely therearound, and placed between the reduced bottom parts d^2 of said fingers and the steel strip d^4 is a supplemental strip d^6 of lead, and in connecting these parts, or in forming the central parts d^2 of the fingers d , the steel strip d^4 is first secured to the part d^2 by the coil d^5 of wire, after which the lead in a liquid condition is poured in to 10 form a strip d^6 , or these parts of said fingers may be formed and connected in any desired manner, and the use of a wire coil in connecting said parts facilitates the operation of said fingers under changes of temperature, or the heating thereof as will be readily 15 understood.

It will be noted that the amount of lead d^6 employed in the construction shown in Fig. 6 is less than the amount employed in Fig. 5, and by changing the amount of lead 20 employed in this connection the degree of heat necessary to operate the fingers d , as hereinafter described, is regulated and the extent of the operation of the fingers is regulated. It being understood that when said strips of lead are made comparatively thick 25 as shown in Fig. 5, the fingers d will make contact with the frame members b^4 under a lower degree of heat than when said fingers 30 are provided with a thin strip of lead as shown in Fig. 6, it being also understood that when a thick strip of lead is employed the fingers will move to a greater extent than when they are provided with a thin strip of 35 lead under the influence of heat by reason of the increase in the expansion thereof.

In Fig. 1 of the accompanying drawing, I have shown two of my improved signal devices connected in parallel, and when used 40 in this way the adjacent ends of the signal devices are connected by circuit wires f which are connected with the corresponding binding posts formed by the corresponding screws c in the adjacent or inner ends of the 45 signal devices, and connected with the binding posts c at the outer ends of the signal devices are main circuit wires g and h , and the main circuit wires g connect with a battery i and the circuit wires h with an electric 50 signal or gong j of any kind or class located at any desired point, but it will be understood that the battery i need not be employed and the wires g may connect with any suitable sort of electric supply, and any 55 desired number of the signal devices j may be employed, but instead of using two or more of my improved signal devices connected in series as shown in Fig. 1, the said signal devices may be used separately or 60 independently as will be readily understood.

The end portions of the hood frame are provided with angular strips k by which the device or devices may be secured to a ceiling or any other suitable support, and in the use 65 of my improved signal device or devices they

are always secured in position so that the open bottom of the hood frame will be directed downwardly and the hot gases of combustion arising from a fire at any point in a room, compartment or space in a building in 70 which one or more of my improved signal devices are employed will enter the hood frame and come directly in contact with the fingers d , and as the central portions d^2 of said fingers are heated the end portions d^3 75 thereof will come in contact with the strips or parts d^4 of the frames b , and the electric circuit will be completed and the signal device or devices j operated, as will be readily understood.

My improved signal device or devices will operate without the use of the wires b^5 and b^6 but said wires are employed for the purpose of rendering the frames b more sensitive, and in order that all parts of said frames may be kept in electrical connection at all times, and especially if said frames or any parts thereof should become broken or disconnected at any time, and with the construction shown it will be seen that the frames b , or the parts thereof, are not in electrical connection at any time, except when the fingers d are in operation, as hereinbefore described, under the influence of heat applied thereto. 95

It will be understood that when the apparatus, or the alarm device or devices are put in operation they will continue to operate until the cooling or contraction of the fingers d takes place, or until the circuit is broken, which latter may be accomplished by means of a suitable switch device, as in the application hereinbefore referred to, or in any other way.

In practice, or in the use of my improved signal device or devices the same are usually placed in such positions as to readily receive the hot gases of combustion arising from a fire in any part of a room or compartment in which said device or devices 105 are placed, and the hood frame is employed for the purpose of directing said hot gases into contact with the fingers d so as to insure the quickest possible operation of said fingers. 110

My invention is not limited to the exact details of the construction of the frame members d herein shown and described, nor to the construction of the hood frame a , and various changes in and modifications of these features of my improved signal device or devices as well as other parts thereof may be made, within the scope of the appended claims, without departing from the spirit of my invention or sacrificing its advantages. 115

Having fully described my invention, what I claim as new and desire to secure by Letters Patent, is:—

1. In a device or apparatus of the class described, a contact finger the central portion 130

of which is composed of three separate metals placed one upon another and having different degrees of expansion and contraction under the influence of heat, the expansion and contraction of the central metal being greater than that of either of the other two.

2. In a device or apparatus of the class described, a contact finger the central portion of which is composed of three different metals having different degrees of expansion and contraction under the influence of heat, and the central part of said finger being composed of lead.
- 10 3. In an apparatus of the class described, a contact finger composed of a main part having a central weakened portion in connection with which is employed a supple-

mental strip of steel and between which parts is placed a strip of lead.

4. In an apparatus of the class described, a contact finger composed of a main part having a central weakened portion in connection with which is employed a supplemental strip of steel and between which parts is placed a strip of lead, all of said parts being secured together by a wire wrapped therearound.

In testimony that I claim the foregoing as my invention I have signed my name in presence of the subscribing witnesses this 27th day of November 1916.

ALEXANDER GIACCONE.
